(57) **CLAIM**

The ornamental design for a right angular waveguide to coaxial adapter, as shown and described.

DESCRIPTION

FIG. 1 is a perspective view of a right angular waveguide to coaxial adapter design showing my new design.

FIG. 2 is a front view of a right angular waveguide to coaxial adapter.

FIG. 3 is a rear view of a right angular waveguide to coaxial adapter.

FIG. 4 is a left side view of a right angular waveguide to coaxial adapter.

FIG. 5 is a right side view of a right angular waveguide to coaxial adapter.

FIG. 6 is a top view of a right angular waveguide to coaxial adapter; and,

FIG. 7 is a bottom view of a right angular waveguide to coaxial adapter.

The broken lines and unshaded areas depict portions of the right angular waveguide to coaxial adapter that form no part of the claim.

Any shading and cross-hatching are not features of the design but are utilized to illustrate the surface contours of the right angular waveguide to coaxial adapter design in the drawings.
